(57) CLAIM

The ornamental design for a desk cleaner brush, as shown and described.

DESCRIPTION

FIG. 1 is a front view of a desk cleaner brush design showing my new design.

FIG. 2 is a rear view of a desk cleaner brush.

FIG. 3 is a left side view of a desk cleaner brush.

FIG. 4 is a right side view of a desk cleaner brush.

FIG. 5 is a top view of a desk cleaner brush.

FIG. 6 is a bottom view of a desk cleaner brush.

FIG. 7 is a front right prospective view of a desk cleaner brush.

FIG. 8 is a bottom rear right prospective view of a desk cleaner brush; and,

FIG. 9 is an exploded perspective view of the desk cleaner brush showing alternative cleaning tools.

The broken line showing in the drawings is for the purpose of illustrating portions of the desk cleaner brush and forms no part of the claimed design.

1 Claim, 9 Drawing Sheets
